B. ROSENFELD.

APPARATUS FOR CHECKING RUNAWAY HORSES.

APPLICATION FILED FEB. 28, 1917.

1,232,092.

Patented July 3, 1917.

UNITED STATES PATENT OFFICE.

BERNARD ROSENFIELD, OF NEW YORK, N. Y.

APPARATUS FOR CHECKING RUNAWAY HORSES.

1,232,092.

Specification of Letters Patent.

Patented July 3, 1917.

Application filed February 28, 1917. Serial No. 151,485.

To all whom it may concern:

Be it known that I, BERNARD ROSENFIELD, a citizen of the United States, and a resident of the city of New York, borough of 5 Manhattan, in the county and State of New York, have invented a new and Improved Apparatus for Checking Runaway Horses, of which the following is a full, clear, and exact description.

10 Among the principal objects which the present invention has in view are: to provide means of the character described operable independently of the weight or traction condition of the vehicle to which the team 15 is attached; to regulate the force applied for the performance of the function above indicated; and to simplify and reduce the cost of the construction and installation of the apparatus.

20 Drawings.

Figure 1 is a side view partly in section of a horse-drawn vehicle having applied thereto means for checking the team, said means being constructed and arranged in accordance with the present invention;

Fig. 2 is a horizontal section on an enlarged scale, the section being taken as on the line 2-2 in Fig. 1;

30 Fig. 3 is a cross section on an enlarged scale, the section being taken as on the line 3-3 in Fig. 1.

Description.

As seen in the drawings, the motive power 35 supplied for the stopping means are the springs 8. The springs are preferably placed parallel to the reach bar 9 of the vehicle. In the preferred form of the invention, the free ends of the springs are 40 connected by a spreader bar 10 that is held in sliding relation with the reach bar 9 by a loop 11. The spreader bar 10 is operatively connected with the winch drum 12, pivotally mounted in brackets 13 pendent 45 from the under side of the box body of the vehicle. Means for connecting the spreader bar and winch drum embody a yoke 15 and a cable 16, the free end of which is connected by a ring 17 with the yoke, while 50 the opposite end is made fast to the winch drum 12.

As shown best in Fig. 3 of the drawings, the winch drum is provided with a fixed bevel wheel 18. The teeth of the wheel 18 are meshed with the teeth of a corresponding pinion 19. The pinion 19 is fixed at the lower end of a crank shaft 20. The crank shaft 20 extends above the floor of the body 14 and at the upper end has a handle 21. To steady the action of the shaft 20, a bearing bracket 22 is suitably attached to the dash of the vehicle body, as shown best in Fig. 1 of the drawings. By rotating the shaft 20, the cable 16 is wound on the winch drum 12 and the spreader bar 10 is drawn 60 forward until the cables 23 are slackened to remove all pressure on the bit in the mouth of the horse to which the free ends of the lines are attached.

To hold the bar 10 in the advanced position, the pawl 24 is pivotally mounted adjacent the wheel 18 and provided with a latch head adapted to engage the ratchet teeth 25 with which the wheel 18 is provided.

As shown best in Fig. 1 of the drawings, 75 the pawl 24 is held actively related to the ratchet teeth 25 by a spring 26. The result of this arrangement is that when the driver rotates the shaft 20, the drum 12 operates to wind the cable 16 and the pawl 24 engages successively the teeth 25 to prevent the retraction of the drum 12 and the relaxation of the cable 16 wound thereon.

The above described disposition of the parts is what may be termed the inactive 85 position. The apparatus is called into action when the driver presses on the pad 27 at the end of the lever 28. The lever 28 is pivoted in a bracket 29, with the free end of the lever resting under the tail-piece 30 90 of the pawl 24. The lifting of the tail-piece of the pawl 24 withdraws the latch head of the said pawl from engagement with the teeth 25, thereby permitting the springs 8 to retract the bar 10 and cables 23 connected 95 therewith.

As shown in Fig. 1, the sudden contraction of the springs 8 draws upon the cables 23 and the bit in the mouth of the horse, irresistibly pulling the chin inward to 100 crook the neck to an uncomfortable position and one which would distract the

horse's attention and cause him to stop. The driver may at any moment when the horse has been checked in his running, relieve the strain on the cables 23 by turning 5 the shaft 20 to draw forward the bar 10. To prevent wear on the cables 23 and to avoid unnecessary friction, the rollers 31 are suspended in bearings provided in the 10 brackets 32 at the forward end of the vehicle body. If it is found necessary, other guiding and friction-reducing devices may be employed for supporting or guiding the lines 23.

15 While I have herein described the invention in its application to a single horse team, it will be understood that it may be applied with equal facility to a team consisting of two or more horses.

Claims.

spreader bar operatively connecting the ends of said springs and a cable operatively connecting said spreader bar and said winch; and manually-operative means for holding 5 said winch for preventing the reverse rotation thereof for unwinding said cable, said means embodying a ratchet wheel mounted

on said drum, a pawl mounted adjacent thereto for engaging the teeth of said wheel, and a tripping lever engaging said pawl, the 10 free end of said lever being disposed adjacent the driver's seat on the vehicle furnished with the above-described apparatus.

BERNARD ROSENFELD.
